UNITED STATES PATENT OFFICE.

SIEGFRIED G. MARSHUTZ, OF LOS ANGELES, CALIFORNIA.

DESIGN FOR A SPECTACLE OR EYEGLASS TEMPLE.

SPECIFICATION forming part of Design No. 29,868, dated December 27, 1898.

Application filed November 3, 1898. Serial No. 695,404. Term of patent 14 years.

To all whom it may concern:

Be it known that I, SIEGFRIED G. MARSHUTZ, a citizen of the United States, residing at Los Angeles, in the county of Los Angeles and State of California, have invented and produced a new and original Design for a Spectacle or Eyeglass Temple, of which the following is a specification, reference being had to the accompanying drawings, showing 10 the same.

Figure 1 is a perspective outline view of a spectacle and eyeglass temple, showing my design as seen from the side. Fig. 2 is a view of the same when looked at somewhat more 15 from the rear. Fig. 3 is a rear view. Fig. 4 is a sectional view on line 4 4, Fig. 1, looking in the direction of the arrow.

As shown in the drawings, the leading or material feature of my design consists of a stem S, having at one end a semiconical body A. 20 a indicates the base, and a' the apex, of the body, to which apex the temple-stem S is attached.

a'' indicates the upper rear face of the body. Having described my invention, what I 25 claim as new, and desire to secure by Letters Patent, is—

The design for a spectacle and eyeglass temple substantially as shown and described.

SIEGFRIED G. MARSHUTZ.
